UNITED STATES PATENT OFFICE.

JOSEPH COUPAL AND RICHARD STEPHENSON, OF WOLLASTON, MASSACHUSETTS.

DEVICE FOR INKING THE SOLE-EDGES OF BOOTS OR SHOES.

SPECIFICATION forming part of Letters Patent No. 371,434, dated October 11, 1867.

Application filed February 4, 1867. Serial No. 226,604. (No model.)

To all whom it may concern:

Be it known that we, JOSEPH COUPAL and RICHARD STEPHENSON, of Wollaston, Quincy, in the county of Norfolk and State of Massachusetts, have invented certain new and useful Improvements in Devices for Inking the Edges of Soles of Boots and Shoes, of which the following is a specification.

Our invention relates to contrivances for "inking" the edges of boot and shoe soles.

It is the object of our invention to provide a machine adapted to perform the work mentioned, which may be operated by power and be convenient and effective in use, and enable 15 an operative to ink the edges of the soles of boots and shoes with great rapidity and without liability of getting any of the ink or coloring-liquid on the uppers or bottom surface of the sole.

To these ends our invention consists in the machine and the combination of parts in the same, which we will now proceed to describe and claim.

Reference is to be had to the accompanying 25 drawings, and to the letters of reference marked thereon, forming a part of this specification, the same letters indicating the same parts wherever they occur.

Of the drawings, Figure 1 represents an end 30 view of our invention. Fig. 2 is a longitudinal vertical section of the same.

In carrying out our invention we provide a reservoir, *a*, of preferably cylindrical form suitably supported upon a base, *A*, and mount 35 in bearings of any proper character formed in the ends of the reservoir a shaft, *b*, having arms or blades *c* secured thereto in the reservoir.

d indicates a roller having a flat periphery also secured to shaft *b* within the reservoir and at one end thereof, as shown in Fig. 2, said roller *d* being so arranged as that its periphery shall roll in contact with the periphery of a similar though smaller roller, *e*, secured on the end of a shaft journaled in suitable bearings above and outside of the reservoir.

g indicates a toothed gear secured on or near the end of shaft *f*, opposite the end to which 45 roller *e* is attached thereto, and said gear *g* is

engaged and driven by a gear, *h*, on shaft *b*, as shown.

i represents a guide of such form and character as to adapt it to move in the crease formed between the sole and upper of a boot 55 or shoe. Said guide may form a part of the end of the reservoir or be detachably connected therewith. Over roller *e* and adapted to move in ways formed in the frame of the reservoir *a* is another guide, *j*, held pressed 60 forward toward guide *i* by a spiral spring, *k*, arranged in a chamber formed in an extension of the frame and bearing against the rear end of said guide *j*.

A neck or extension, *l*, is formed on the 65 rear of the reservoir, as shown in Fig. 1, which neck is provided with an aperture or hole communicating with the interior of the reservoir, and a screw-cap, *m*, is fitted on the upper end of said neck to close the same. 70

The peripheries of rollers *d* and *e* may be provided with a yielding covering of any suitable character.

The operation of our invention is as follows: Reservoir *a* being supplied with ink through 75 the aperture formed in neck *l*, and cap *m* being screwed in place, shaft *b* is rotated in any suitable way, which operation carries around wings or arms *c*, and so keeps the ink stirred up or agitated to prevent the precipitation or 80 settling of the heavier particles therein. The same operation rotates roller *d*, having a portion of its periphery immersed in the ink, by which means ink is supplied to the periphery of roller *e* on shaft *f*, rotated by the engagement of gear *g* with gear *h*. The shoe to be treated is placed with the face of the sole 85 against the forward end of guide *j*, with the edge resting on the periphery of roller *e*, and with guide *i* in the crease between the sole and upper. In this position the shoe is moved around so that all parts of the edge of the sole are brought in contact with the periphery of roller *e*, upon which the ink has been evenly and thoroughly distributed by roller *d*. Guide 90 *i* effectually prevents the ink or coloring-liquid from being applied to the upper, and the yielding connection of guide *j*, with its support, permits of a sole of any thickness being treated, and at the same time holds the sole 95

100

securely in place against guide *i* and keeps the coloring-liquid from being applied to the lower surface of the sole.

Suitable stuffing-boxes, *n*, may be provided 5 on the ends of the reservoir around shaft *b* to prevent the ink from leaking or creeping out on the latter.

While we have been particular to describe 10 the form and arrangement of all the parts here shown, it is obvious that these may be changed without departing from the nature or spirit of the invention.

What we claim is—

1. In a machine for inking the edges of soles 15 of boots and shoes, the reservoir, a rotating shaft journaled therein, agitator blades or arms secured to said shaft in said reservoir, an ink-supply roller also secured to said shaft, and a sole-edge-inking roller arranged to have 20 its periphery roll in contact with the periphery of the supply-roller, combined, constructed, and operating substantially as and for the purposes hereinbefore set forth.

2. In a machine for inking the edges of soles 25 of boots and shoes, the reservoir, a rotating shaft journaled therein and provided with blades or wings for agitating the ink, the ink-supply roller, a sole-edge-inking roller arranged to have its periphery roll in contact 30 with the periphery of the supply-roller, and a guide adapted to enter the crease between the sole and upper of the boot or shoe, all con-

structed, combined, and operating as and for the purpose hereinbefore set forth.

3. In a machine for inking the edges of soles 35 of boots and shoes, an ink-supply roller, a sole-edge-inking roller, a guide adapted to enter the crease between the sole and upper of the boot or shoe, and a spring-pressed guide adapted to bear against the lower face of the 40 shoe-sole, constructed, combined, arranged, and operating substantially as hereinbefore set forth.

4. In a machine for inking the edges of soles 45 of boots and shoes, a reservoir, shaft *b*, provided with ink-agitating blades *c*, roller *d*, shaft *f*, roller *e*, and gear-wheels *g* and *h*, constructed, combined, and operating substantially as described.

5. In a machine for inking the edges of soles 50 of boots and shoes, an ink-supply roller, a sole-edge-inking roller, *e*, guide *i*, guide *j*, and spring *k*, all constructed, combined, and operating substantially as set forth.

In testimony whereof we have signed our 55 names to this specification, in the presence of two subscribing witnesses, this 17th day of January, A. D. 1887.

JOSEPH COUPAL.
RICHARD STEPHENSON.
